G. A. CARUELLE,
 MULTICELLULAR ARRANGEMENT FOR THE RAISING OF LIQUIDS,
 APPLICATION FILED OCT. 16, 1919.
1,417,886. Patented May 30, 1922.

UNITED STATES PATENT OFFICE.

GEORGES ALBERT CARUELLE, OF PARIS, FRANCE.

MULTICELLULAR ARRANGEMENT FOR THE RAISING OF LIQUIDS.

1,417,886.

Specification of Letters Patent. Patented May 30, 1922.

Application filed October 16, 1919. Serial No. 331,253.

(GRANTED UNDER THE PROVISIONS OF THE ACT OF MARCH 3, 1921, 41 STAT. L., 1312.)

To all whom it may concern:

Be it known that I, GEORGES ALBERT CARUELLE, citizen of the Republic of France, residing at 10 Rue Lasson, at Paris, Seine, France, have invented certain new and useful Improvements in Multicellular Arrangements for the Raising of Liquids (for which I have filed application in France, Patent #484,516, granted Oct. 16, 1917), of which the following is a specification.

Endless bands are known for elevating liquids which are provided with arrangements such as sponges wires, metallic trellis of various shapes, conveniently disposed in such a manner as to retain the liquids.

The present invention aims at the production of an apparatus of this kind having a band of metal or other resilient material folded in the direction of its width so as to 20 constitute a large number of cells. In addition to being economical, this band has the advantage of permitting the greatest proximity of the partitions with respect to each other, this being more difficult to obtain 25 with separate strips and which is an advantage in retaining the liquid; it has been proved that with undulated bands according to this invention, the cells, thus obtained, retain the liquid without waste and that if 30 an excess of water should overflow from one of them, such overflow would invariably be caught by the next lower cell.

Experiment has shown that in order that a band made according to this invention 35 should give the best results, that is to say that the liquid should be raised without loss, it is preferable for the cells to have a wedge-shaped shape and should be in contact with each other separated only by a thin strip so 40 as to reduce to a minimum the transverse action of the air and so that the band shall form only a series of small reservoirs super- 45 posed one above the other and on which the air current, produced by the ascension, has no effect. It will be seen that this construc- 50 tion favors to the highest degree the phe- nomenon of capillarity and enables the rais- 55 ing of the liquid without loss. It therefore offers certain advantages over existing ap- pliances more so because several bands can 60 be made to work at the same time side by side. The band or bands may, if desired, be secured to a convenient support such as a chain, cable, canvas belt made of leather, 65 hemp, caoutchouc or of any other material.

Where an undulated band with a support, is adopted, the same is readily secured to the belts chains or cables; to the belts by means of rivets at intervals of about 5 cms.; to the chains it is fixed by links which suffice in spite of the distance between the points of attachment because it holds of its own accord; with regard to the fixing to the cables a metallic band is utilized which surrounds the strands of the band itself.

In the accompanying drawings several methods of carrying the invention into effect have been shown by way of example.

Fig. 1 shows a portion of this band undulated in such a manner as to form very close cells.

Fig. 2 is a face view showing how to secure the undulated band to a flat belt serving for support.

Fig. 3 is a side view, the undulated band being secured to the belt.

Fig. 4 shows a front view of two bands secured side by side to work together.

Fig. 5 shows a front view of two bands fixed side by side on a support.

Fig. 6 shows a face view of a larger band secured to a support.

Fig. 7 shows a front view of a band secured to a flat cable and

Fig. 8 shows a band secured to a chain.

It will be seen that if with an undulated band, as shown in Fig. 1, the walls *a* of the various cells *b* are sufficiently close together, these cells retain liquid by capillary action without loss when, after immersing the band in the liquid it is withdrawn therefrom; this results from the fact that the band has no break of continuity and on the other hand, if an excess of liquid should escape from one of the cells it will be immediately caught by the lower cells.

The band without break of continuity, folded back on itself can be economically produced by machine and when secured on a carrying pulley operates perfectly for raising liquids.

It can advantageously be made of aluminum which reduces the weight and practically renders it non-oxidizing.

It can also be used, secured to a support formed by an endless chain, or better, by an endless belt, the chain or the belt resting on a carrying pulley. It can be fixed to this belt, marked *c* in the drawing either edge-wise or flat.

All the walls being integral, the points of attachment can be sufficiently far apart and these attachments may be either hooks *d* or rivets *e*. If the points of attachment are worn by the liquid and lose their security in the attachment of the belt, it can be secured at other points without changing the chain itself.

In order to increase the output one can cause two or more undulated bands as shown in Fig. 4 to work together, leaving between them sufficient space so that the filling and emptying can take place normally. Both bands can be held together by convenient means, for example by a metallic band *r* or otherwise, Fig. 5. Several bands can also be made to operate at the side of each other without being held together by providing or not, grooves in the driving pulley.

Fig. 6 shows that the band can be larger and have openings such as *f* taking the full height of the cells and conveniently spaced.

Fig. 7 shows the method of fixing a band to a cable, it being sufficient for the purpose to surround the cable or band with a metallic band *s* which fixes them together.

Fig. 8 shows how a band can be mounted on a chain.

It must be understood that any other arrangement where the cells are obtained by folded or undulated strips or forming independent elements secured in similar fashion and giving analogous results would come within the scope of this invention although not possessing the advantages relative to the fixing and construction, as the continuous band.

Having now described the nature of my invention what I claim is:

1. A band continuous throughout and formed of flexible material folded back upon itself in the sense of its width to constitute a series of cells of practically wedge shape superposed upon each other and separated by a thin wall offering but slight resistance to the lateral air. 45

2. A band continuous throughout and formed of flexible material folded back upon itself in the sense of its width to constitute a series of cells of practically wedge shape, 50 superposed upon each other and separated by a thin wall offering but slight resistance to the lateral air, said band adapted to be used alone or fixed flat or edgewise on a support as a flat endless belt or chain so that the band can by plunging with its part in the liquid, fill the cells by simple immersion, retain the liquid by capillary action during the ascent and empty by centrifugal action and its weight. 60

3. The form of band as under claim 1, together with a plurality of supports each carrying one of such bands.

4. A multiplicity of bands as under claim 1, and a support to which they are affixed. 65

5. A multiplicity of bands as under claim 1, and a support to which said bands are attached, said support being a flat metallic cable composed of strands united together.

In testimony whereof I affix my signature 70 in the presence of a witness.

GEORGES ALBERT CARUELLE.

Witness:

CHAS. P. PRESSLY.
